WHEEL

Thomas L. Hibbard, Birmingham, Mich., assignor to Kelsey-Hayes Company, Romulus, Mich., a corporation of Delaware

Filed Nov. 17, 1961, Ser. No. 67,567

Term of patent 14 years

(Cl. D14—30)

FIG. 1 is a perspective of a wheel, showing my new design; and

FIG. 2 is a diametrical cross-section through the wheel.
The dominant features of my design reside in the portions shown in full lines.

I claim:

The ornamental design for a wheel, substantially as shown and described.
